UNITED STATES PATENT OFFICE.

HERBERT J. TRAVIS, OF NEW YORK, N. Y.

FUEL-FEEDING APPARATUS.

No. 823,563.

Specification of Letters Patent.

Patented June 19, 1906.

Application filed September 7, 1905. Serial No. 277,313.

To all whom it may concern:

Be it known that I, HERBERT J. TRAVIS, a citizen of the United States, and a resident of the borough of Brooklyn, in the city and State of New York, have invented a new and useful Fuel-Feeding Apparatus, of which the following is a specification.

My invention relates to fuel-feeding apparatus, and more particularly to means for delivering the pulverized material from the pulverizing-cylinder to the furnace; and it consists, broadly, in providing the periphery of the cylinder, near its discharge end, with a passage-way extending in a tangential direction from the periphery of the cylinder and curving into the plane of the longitudinal axis of the cylinder, extending thence away to the point where the pulverized material is to be used.

20 A practical embodiment of my invention is represented in the accompanying drawings, in which—

Figure 1 is a side view of a portion of a pulverizing-cylinder, showing it in side elevation with the discharge-conduit leading therefrom. Fig. 2 is a similar view in top plan representing two discharge-conduits diametrically located with respect to each other, and Fig. 3 is a transverse section in the plane of 30 the line A A of Fig. 2.

The pulverizing-cylinder, in which the material to be fed to the furnace is reduced to a finely-pulverized or floured condition, is denoted by 1. At its discharge end it is provided with one or more discharge-conduits, in the present instance two, which extend from its periphery in a tangential direction, as denoted at 2 and 3, in the present instance at points diametrically opposite each other 35 and which after following the curve of the cylinder a short distance (denoted at 4 and 5) gradually curve into the plane of the longitudinal axis of the cylinder, as shown at 6, Fig. 1, and then gradually converge, as shown 40 at 7 and 8, Fig. 2, until they unite and form a single discharge-passage 9, which may be continued directly either in a right line or in

suitable curved lines, as the case may be, to the point where the fuel is to be burned in the furnace. The size of the discharge-conduits 50 leading from the cylinder will naturally depend upon the number of such conduits employed, which may be one or more, but preferably two, as shown.

It has been found by experience that the 55 pulverized fuel will be naturally discharged in a tangential direction under centrifugal force at the periphery of the cylinder with greater conformity and freedom than at any other point, and at the same time it becomes 60 important, particularly in connection with locomotives, that the flow of the pulverized material should be in a direction corresponding to the longitudinal axis of the pulverizing-cylinder at a point as near the discharge end 65 of the cylinder as may be feasible. To this end I have provided the curved conduits which utilize the centrifugal action to start the flow and then promptly convert it by a gradual turn into a flow directly away from 70 the cylinder in the longitudinal direction of the same.

What I claim is—

1. The combination with the cylinder, of a discharge-conduit extending tangentially 75 from the periphery of the cylinder and gradually curved into a position extending in a direction corresponding to the longitudinal axis of the cylinder.

2. The combination with the cylinder, of 80 a plurality of discharge-conduits extending tangentially from the periphery of the cylinder and gradually curved and merged into one conduit extending in a direction corresponding to the longitudinal axis of the cylinder. 85

In testimony that I claim the foregoing as my invention I have signed my name, in presence of two witnesses, this 21st day of July, 1905.

HERBERT J. TRAVIS.
